DISHWASHING APPARATUS

Emmett J. Culligan and Thomas E. Culligan, San Bernardino, Calif., assignors to E. J. Culligan Benevolent Foundation, San Bernardino, Calif.

Application June 6, 1947, Serial No. 753,070

3 Claims. (Cl. 259—4)

1

Our invention relates to a dish washing apparatus. The object of the invention is to provide a compact container adapted to be set upon the drainboard of a kitchen sink so as to discharge the waste water into the sink, and to create in this container a violently moving body of intimately mixed air and water which moves in a revolving mass generally upwardly to discharge at the top of the container. The container preferably employs no racking means, and the dishes are placed therein indiscriminately as taken from the table, except, of course, that dishes of the same order—plates, saucers, glasses—are not nested. There is no moving part within the container. The violent movement of intermixed air and water is obtained from a jet of water from the household water supply passing through a nozzle or Venturi tube to which air is admitted from outside the container preferably from a point above the level of the upper part of the container.

Heretofore, dish washing apparatus has been complicated and expensive, embodying moving parts, which, because they operate in water, quickly get out of order. Such machines have always required, as an absolute necessity, racking means in the container for holding the dishes in predetermined fixed spaced positions. This has resulted in dish washing machines of limited capacity, which are too expensive to be purchased for families of an average, moderate income, which, because of the necessity for racking the dishes, have such limited capacities that they are not available for large families, and which are time-consuming in arranging the dishes on the racks, tend to bring about breakage of dishes and have never been entirely effective for completely cleaning the dishes, because the sprayed water can hit directly only one wall of the dish.

In the present invention we have provided a relatively simple dish washing apparatus for domestic use which incorporates a container of generally cylindrical outline which is adapted to receive table dishes in an unnested condition and preferably without racking. A mixture of air and water is introduced into the container through a nozzle which penetrates the container adjacent its lower extremity and is arranged to inject the mixture in a revolving mass which rises over the dishes while passing in intimate contact with all of the surfaces of the dishes. As the revolving mass of mixed water and air together with a suitable detergent passes over the dishes the food particles and residual matter is cleaned from the dishes and is either entrained in the cleaning

5 solution or will float on the upper surface thereof and by virtue of the revolving action of the cleaning solution will tend to move towards the outer wall of the container. A large weir-like opening is provided in the container adjacent its upper extremity through which the detergent solution and the residual particles may pass outwardly for disposal and without creating pressure within the container. The container is also provided 10 with a relatively large disposal outlet duct adjacent its lower extremity and at one side of the nozzle so as to dump or dispose of all the detergent solution after the dishes have been properly washed and while water and air are still being introduced through the nozzle.

15 We have found by this arrangement that table dishes may be suitably and quickly washed with the use of a relatively small quantity of water and using only a relatively small amount of 20 detergent material. The revolving mass of water, air and detergent suds forms a scrubbing action on all of the surfaces of the dishes, and the air particles carried in the mixture aids in producing an extraordinarily efficient cleaning action which 25 is not found when water is used alone or merely in admixture with detergent.

30 We further discovered that, while a degree of dish washing efficiency may be accomplished with our invention where ordinary tap water is used, far better results follow the use of soft water, that is, normally water from the system which has been passed through what is known as a zeolite water softener. That is, an arrangement such that the water passes through a bed of zeolite and the minerals which produce hardness are removed therefrom. With the use of such 35 hot soft water, the complete washing of all the ordinary dishes used in connection with a home meal may be effected in a few minutes' time.

40 An object of the present invention is to provide a domestic dishwasher in the form of a container having a substantially cylindrical inner wall in which a mixture of air and water is introduced into the container adjacent its lower extremity 45 through a nozzle which is disposed to form a revolving rising mass that is adapted to pass upwardly over a group of dishes to cleanse the surface of the dishes and in which the excess of the mass is discharged through a large opening in the container adjacent its upper extremity until 50 the dishes are cleansed, after which the remainder of the mass is rapidly disposed of through a second large opening in the container adjacent its lower wall, and while water and air are still being injected into the container.

Another object of our invention is to provide a dish washing apparatus embodying a container wherein the entire space within the container is available for receiving dishes and into which the dishes may be placed without racking.

It is a further object of our invention to provide means adapted to be connected with the hot water faucet of a water system, wherein the hot water has been softened before coming to the faucet, and providing means for delivering the water into the bottom of the container intimately mixed with large volumes of air.

It is a further object of our invention to employ a jet nozzle, in association with a Venturi tube and with an air delivery tube, to produce the aforesaid mixture of water particles and air.

It is a further object of our invention to provide an overflow outlet near the top of the container such that the intermixed water and air and the suds from soap employed will gradually be expelled from the container until the water therein is freed from soap and substantially freed from matter removed from the dishes.

It is a further object of our invention to provide an outlet at the bottom of the container together with means for holding it closed when the washing operation is taking place and for opening it to permit drainage from the container, while the injection of water and air from the Venturi tube continues to take place.

The full objects and advantages of our invention will appear in connection with the detailed description thereof given in the appended specification, and the important and advantageous novel features of our invention will be particularly pointed out in the claims.

In the drawings,

Fig. 1 is a schematic elevation of our invention as applied and used in connection with a standard kitchen sink and a water system adapted to furnish softened hot water.

Fig. 2 is a top plan view of our invention in position on the drainboard of a kitchen sink.

Fig. 3 is a sectional view taken on line 3—3 of Fig. 2.

Fig. 4 is a sectional elevation view taken of the structure shown in Fig. 2 and showing a general view of the dishes in the container.

Fig. 5 is an elevation view of the washing appliance viewed toward the discharge and drainage openings.

Fig. 6 is a sectional elevation view showing the bottom drainage duct closed.

Fig. 7 is a sectional elevation view similar to Fig. 6 showing the bottom drainage duct held open.

As illustrated in Fig. 1, a sink cabinet 10 is provided with a sink 11 (illustrated in dotted line), with drainboards 12 and 13, and storage cabinets 15 and 16. A faucet 17 is adapted to deliver cold water from a water system by means not shown. A faucet 18 is adapted to deliver hot water.

The water going to faucet 18 is delivered from a conventional water system through a pipe 19, to a zeolite water softener 20 through which the water is slowly caused to move from the lower part of the tank 20 through beds of zeolite (not shown) within tank 20 to a discharge pipe 21 substantially at the top of the water softener tank 20.

The pipe 19 is removably secured at 22 to the tank 20 and the pipe 21 likewise is removably secured at 23 to the tank 20. A valve 24 shuts off the water to pipe 19 and a valve 25 shuts off

the water to pipe 21 and an extension 26 thereof which at 27 enters a water heater 28.

The purpose of the above described arrangement of removable connections and closure faucets is to permit the softener tank 20 and its contents readily to be removed and replaced by another tank with reactivated or fresh zeolite therein, whenever the zeolite in the tank becomes vitiated by continued use.

10 The water heater 28 may be any standard water heater such for example as a gas heater supplied with gas from a pipe 30 which heats the water going through it to a quite high temperature before it is delivered from the water heater to a delivery pipe 31. The pipe 31, as shown schematically in Fig. 1, delivers to and through faucet 18 normally to discharge into the sink 11.

15 The water, from the softening apparatus used, in cooperation with the hot water coming from the means above indicated, goes through a removable pipe connection 33 into a dish container 34 in a manner which will hereinafter be described. The dish container 34 is a member having vertically extending cylindrical walls 34', a flat bottom 35, and a rolled-over top edge 36. A cover member 37 of any desired standard construction is provided with a down-turned annular flange 38 which has a reasonably tight fit over the turned-over edge 36. A handle 39 on the top of cover 37 adapts the cover readily to be placed in position as a closure for the container 34 or removed therefrom to open the top for free access when the dishes are placed within the container and taken therefrom. Container 34 is provided with side handles 82, 83.

20 The means of delivering the water to the chamber 40, formed by the cylindrical walls 34', the bottom 35 and the cover 37, is shown in section in Figs. 3 and 4 and in plan in Fig. 2. These 25 means comprise an aspirator or Venturi nozzle indicated by general reference numeral 41 composed of a tubular casting 42 having an annular flange 43 for securing the casting 42 to the cylindrical wall 34', and having formed therein a chamber 44 with a conical extension 45 which opens through a narrowed opening 46 into a tube discharge extension 47.

25 The direction in which the extension 47 extends into the chamber 40 is tangentially along the inner cylindrical wall 34' of the container 34 and produces a whirling vortex which brings the violently moving water and air against all surfaces of the dishes no matter how they may be placed in the container.

30 The Venturi arrangement, Figs. 3 and 4, includes a second casting 48, which has a central passageway 49 leading to a nozzle 50. This nozzle is provided with a small opening 51 directed into the chamber 44 along the axial center of the tube 35. The casting 48 has an annular flange 52 which seats against the cylindrical top end 53 of the casting 42 and is threaded externally to screw into the internally threaded end of casting 42 and bring the flange 52 firmly in contact with the end wall 53 of said casting.

35 A packing nut 54 of usual construction has its internally extended annular flange 55 in engagement with an annular flange 56 forming part of an outwardly extending nipple 57. The packing nut is internally threaded and is screwed upon external threads formed about the outer portion of casting 48. A gasket 58 between the flanges 55 and 56 produces a water and air-tight seal about the internal passageway 49 through 40 nipple 57 to the chamber 49 within casting 48.

The hose 33 is of elastic material such as rubber, and has an expansion fit on the nipple 57. The other end of this hose has a removable screw-set, leak-tight connection at 33' with the hot water faucet 18.

A tube 60 is provided with an open-topped air vent 61 which opens into chamber 44 as clearly shown in Fig. 5. This tube is supported at its bottom on casting 42 and may be supported towards its top by a bracket member 63.

The above construction provides what is known as an aspirator or venturi in which water under substantial pressure such as is found in practically all water systems, discharges at high speed through the jet opening 51 across the expanded chamber 44. This jet seizes the air entering the chamber 44 through tube 60 and discharges the air and water as an intimate mixture through the extension 47.

The water and air enter the washing chamber 40 at the end 62 of the Venturi tube 47, and the mixture of water and air is moved through the chamber 40 and about the dishes therein in a violently turbulent surge of hot water and air in a revolving mass which brings the mixed water and air about all surfaces of the dishes, no matter how they have been placed in the container.

In practice, a small amount of soap, less than a teaspoonful of any standard powdered soap or soap flakes, is indicated at 63 of Figs. 2, 3, and 4, as being placed on the bottom 35 in line with the stream of mixed water and air from the venturi. This soap is immediately taken up by the in-rushing air and water. This mass quickly fills chamber 40, and contacts all surfaces of the dishes as placed indiscriminately within chamber 40 in the container.

At the top of said chamber and below the cover is an elongated rectangular weir-like opening 64 shown in cross section in Figs. 3, 4, 6 and 7, and in full elevation in Fig. 5. As shown in Fig. 1, the opening 64 is faced toward the edge of the drainboard into sink 11.

Container 34 is provided with a large drainage valve 65 shown best in Figs. 5, 6 and 7. It comprises a casting 66 adapted to fit and be fastened to the walls 34' and the bottom 35, as indicated at 67 and 68, and is curved to adapt itself to the curved walls 34'. The valve 65 is hinged at 69 to open outwardly to clear an opening 70 from the chamber 40.

A handle rod 71 is freely connected at 72 to a rigid eyepiece 73 on the valve 65. The rod 71 extends through a slot 74 in a bracket 75 secured to and extending outwardly from the upper part of front vertical wall 34'. The rod 71 is provided with a notch 76 which is adapted to engage over a spring member 77 held on the bracket 75 by means of a rivet or screw bolt 78.

A spring 79 engages the lower side of bracket 75 and a retainer ring 80 on the rod 71 normally presses the valve 65 into closing position. When it is desired to open the valve 65, by a handle portion 81 the rod is pulled up and the valve 65 swung to its open position of Fig. 7 until the notch 76 on rod 71 comes above the spring detent 77 on bracket 75, in which position the spring holds the rod with the valve 65 open as heretofore indicated and as shown in Fig. 7.

In operation, container 34 may be manually carried to the table or other place where dishes are located and the dishes placed in the container, preferably in an unracked condition as disclosed in Fig. 4. Thereafter cover 37 is placed on the container and the container is positioned

on one of the drainboards 12, 13 of a conventional kitchen sink in the manner disclosed in Fig. 1. The rubber conduit 33 is initially secured to the hot water faucet 18 by means of the coupling 33' and the other end of conduit 33 is inserted over the outwardly extending nipple 57 of the nozzle 41. A small quantity of detergent is placed in the container 34, preferably before placing the dishes therein, and it will be noted in Figs. 2, 3 and 4 that the detergent is in line with the extension 47 of the nozzle so as to be picked up by water and air being emitted from the nozzle. It will be particularly noted in Figs. 2, 4 and 5 that the nozzle is arranged to inject the air-water mixture into the container 34 so as to form a revolving mass within the container. As shown, this is accomplished by tangentially inserting the nozzle through the side of container 34. When water which has been softened in the water softening tank 20 and heated in the heater 28 enters the nozzle it will be under considerable pressure and will aspirate or draw air from the chamber 44, which air becomes intimately admixed with the water in the extension 47. As the rotating mass rises over the dishes it passes in intimate contact with all of the surfaces thereof and will loosen or scrub residual food particles including grease if the same be present. Centrifugal force of the revolving mass will cause the grease and food particles to be moved outwardly towards the side walls 34' of the container so that when the water level reaches the weir-like opening 64 it will flow by gravity through this opening carrying therewith the residual food particles and grease which will be in a floating condition on top of the water. The washing operation continues for only a short time to assure proper cleansing of the dishes and by actual test it has been determined that softened water containing a detergent and admixed with air, in the manner described, fully and completely cleanses table dishes in a very short time. Thereafter the large gate valve 65 is moved to an open position through means of the manually operable linkage, to permit discharge of the cleansing solution from the bottom of the container and while water and air are still being injected through the nozzle 41. To accomplish this it is, of course, necessary that the opening 70 have a greater discharge capacity than nozzle 41. With the cleansing solution revolving about the dishes we have found that all of the residual material is maintained at the side of the container and does not settle on the dishes as the water level is reduced. The gate valve 65 is maintained in an open position and the operation of the nozzle is continued to assure removal of all residual food particles from the container. Thereafter faucet 18 is closed and tube 33 is removed from the nipple 57, and preferably connected to an ordinary hand held spray nozzle, not shown, to spray hot water over the dishes to assure absolute removal of detergent suds which might have settled on the dishes. Thereafter the dishes are placed in a rack or may, if desired, be placed directly in a storage cabinet.

An advantage of our invention comes from the fact that it uses very little soap, particularly true when soft water is employed, as it should be in the practice of the method of this invention. This contrasts very sharply with other dish washing devices, in which a soap solution is continually added to the water going to the dishes (in sprays of various sorts and kinds) and immediately wastes away. Here all of the soap used is

kept in contact with the dishes, principally in the form of suds. These suds with water and air mixed and in violent motion completely fill the chamber within the container and about the dishes and slowly discharge until the dish washing is fully completed.

The final highly important advantage comes from the fact, which will be obvious from a mere inspection of the invention, that the cost of the complete apparatus is low and hence it can be manufactured and sold at a price which families of moderate means can afford to pay.

We claim:

1. In a dishwasher, in combination, a container having a bottom wall and a substantially cylindrical side wall, a nozzle extending tangentially through the side wall adjacent its lower extremity and having means for discharging a mixture of water and air into the lower portion of the container to form a rising revolving mass within the container, said container adjacent its upper limits having a weir-like discharge passage of greater discharge capacity than the nozzle and forming a free discharge from the upper edges of the mass, said container adjacent its lower limits having a second discharge opening of larger capacity than the discharge capacity of the nozzle for permitting discharge of the mass while the nozzle is operative, and valve means operably associated with said second opening.

2. In a dish washer, in combination a container having a bottom wall and a substantially cylindrical side wall, a nozzle extending from a source of water and air through the side wall adjacent its lower extremity and discharging tangentially into the lower portion of the container to form a rising revolving mass within the container, said container adjacent its upper limits having a large discharge passage of greater discharge capacity than the nozzle and forming a free discharge from the upper edges of the mass, said container adjacent its lower limits having a second discharge opening of larger capacity than the discharge capacity of the nozzle for permitting discharge of the mass while the nozzle is operative, and valve means operably associated with said second opening.

3. In a dish washer, in combination, a container having a bottom wall and a substantially cylind-

rical side wall, a Venturi type nozzle connected to a pressurized source of water and having means for entraining air in admixture with the water, said nozzle extending through the side wall of the container adjacent its lower extremity and discharging the mixture of water and air tangentially into the lower portion of the container to form a rising revolving mass within the container, said container adjacent its upper limits having a discharge passage of greater discharge capacity than the nozzle and forming a free discharge from the upper edges of the mass, said container adjacent its lower limits having a second discharge opening of larger capacity than the discharge capacity of the nozzle for permitting discharge of the mass while the nozzle is operative, and valve means operably associated with said second opening.
